UNITED STATES PATENT OFFICE.

LEWIS CARLISLE MILES, OF BOISE, IDAHO.

WINDING DRUM.

1,408,463.

Specification of Letters Patent. Patented Mar. 7, 1922.

Application filed April 29, 1921. Serial No. 465,526.

To all whom it may concern:

Be it known that I, LEWIS C. MILES, a citizen of the United States, and a resident of Boise, in the county of Ada and State of Idaho, have invented certain new and useful Improvements in Winding Drums, of which the following is a specification.

This invention relates to a winding drum.

In the use of drums for winding cables to which a load is attached, it often occurs that the surface becomes so badly worn that it is unfit for further use, and the drum must be discarded. In such an instance it would be desirable to have a renewable winding surface for the drums. Also it often happens that the same drum is subjected to different loads depending upon the class of work being done, and in these cases, it would be desirable to have a drum of small diameter for heavy work and a drum of relatively larger diameter for lighter work.

Further the load is often light in the beginning and gradually increases as the winding up of the cable proceeds. In these instances, it would be desirable that the diameter of the drum would decrease with the winding of the cable.

With the above in mind, it is the object of the present invention to provide a removable lagging or sheathing for drums by which these desirable features may be had.

Other objects and objects relating to details of construction, combination and arrangement of parts will hereinafter appear in the detailed description to follow.

The invention is illustrated by way of example in the accompanying drawings, in which:

Figure 1 is a side elevation of the drum embodying my invention,

Figure 2 is a transverse section taken substantially on the lines 2—2 of Figure 1,

Figure 3 is a longitudinal section taken substantially on the lines 3—3 of Figure 2,

Figure 4 is a detail sectional view illustrating the connection of the drum and lagging,

Figure 5 is a view similar to Figure 2, but showing a modified form of lagging.

Referring to the drawings in detail, and particularly to Figures 1 to 4 inclusive, 10 and 11 indicate a pair of head members which support the drum 12. The drum 12 in this instance is cylindrical in shape and has formed at each end a pair of diametrically opposed ears or lugs 13. Over the

drum 12 there are fitted two semi-frusto conical sections 14 and 15 which form for said drum, a lagging. These sections when placed about the drum taper toward the 60 head 10 as shown. The outer surface of each lagging section is grooved as at 16, said groove being adapted to register when the sections are in position about the drum and provide a continuous groove for the reception of a cable or rope. Each of the lagging sections are formed with a pair of ears or lugs 17 which are adapted to fit over and register with the lugs 13 formed on the drum 12. The lugs 7 and 13 are provided with 70 registering openings which taper toward the inner ends and said openings are adapted to receive a tapering bolt 18. Each of the bolts also pass through the corresponding heads 10 and 11, and carry on their outer 75 ends a pair of lock nuts 19 by which the drum 12, lagging sections 14 and 15, and heads 10 and 11 may be secured together. The tapering bolts 18 are also adapted for tightening up in case they become loose from 80 constant wear.

In order to further secure the lagging sections together a plurality of bolts 20 (Figures 1 and 2) are positioned for connecting the meeting edges of said sections. 85 The recesses 21 are formed in one of the sections so that the heads of the bolts will be flush with the surface of the groove 16, and not interfere with the winding up of the cable upon said lagging sections. Also 90 the longitudinal edges of one of the lagging sections may be provided with tongues as indicated at 22, and said tongues entering into complementary recesses formed in the adjacent edges of the other lagging section. 95 Again each lagging section may be formed with a projection upon its inner surface as at 23 which would enter a recess formed in the drum 12, and so aid in holding the lagging sections against movement with respect 100 to the drum.

Referring to Figure 5, the construction disclosed is the same as that shown in Figures 1 to 4 inclusive, with the exception that the lagging section 24 is not formed with 105 grooves; also the bolts 20, tongues 22 and projections 23 are dispensed with, and the wedges 25 substituted to serve the same purpose. A pair of wedge members 25 are formed with the head member 10, as shown, 110 and adapted to enter complementary recesses 26 formed in the corresponding end of the

lagging sections. These wedges together with the bolts 18 hold the lagging sections rigidly and securely upon the drum 12.

It is believed from the foregoing description that the objects of my invention can be understood. It may be pointed out however that although I have shown the lagging sections as tapering in shape, I am not to be so limited as the lagging section purely semi-circular in form or shape would in many instances be suitable.

Also it is to be understood that the lagging sections are to be made of different thicknesses so that when placed upon a drum they may have different diameters, and thus be suitable for changing the diameters of drums and making the same adapted to perform different classes of work; that is, a drum of small diameter for lifting a heavy load, and of larger diameter for lifting a lighter load.

I claim:—

1. In combination, a winding drum, a head for each end thereof, a pair of diametrically opposed lugs formed on each end of said drum, a pair of lagging sections adapted to fit over said drum and having lugs extending therefrom adapted to register with the lugs of said drum, and means by which the lugs of said drum and the lugs of said lagging sections may be secured to the head members.

2. In combination, a winding drum, a head for each end thereof, a pair of diametrically opposed lugs formed on each end of said drum, a pair of lagging sections adapted to fit over said drum and having lugs extending therefrom adapted to register with the lugs of said drum, and tapering bolts extending through openings provided in said registering lugs of the semi-cylindrical lagging sections and the drum, and also extending through the corresponding head members, and lock nuts for said tapering bolts by which the drum, lagging sections, and drum heads may be secured together as a unit.

3. In combination, a winding drum, a head for each end thereof, a pair of diametrically opposed lugs formed on each end of said drum, a pair of lagging sections adapted to fit over said drums and having lugs extending therefrom adapted to register with the lugs of said drum, and means by which the lugs of said drum and the lugs of said lagging sections may be secured to the head members, and means by which the adjacent edges of said semi-cylindrical lagging sections may be secured together.

4. In combination with a winding drum, a pair of lagging sections adapted to fit about said drum, a head for each end of the drum, and bolts for securing together

the lagging sections, drum and heads as a unit, each bolt serving to establish a direct connection between a head, a lagging section and the drum.

5. In combination with a winding drum, a pair of lagging sections adapted to fit about said drum, a head for each end of the drum, radial projections extending from said lagging sections and drum, and bolt means adapted to extend through each head and associated radial projections of said lagging sections whereby the drum, lagging section and heads may be secured together as a unit.

6. In combination with a winding drum, a pair of lagging sections adapted to fit about said drum, a separable head for each end of the drum and abutting the associated ends of said lagging sections, radial extensions formed with the lagging sections and drum adapted to extend inwardly at the similar ends of lagging sections and drum adapted to register with each other, means adapted to extend through the radial projections of said lagging sections and drum and also through the heads whereby said heads, lagging sections and drum may be secured together as a unit.

7. In combination with a winding drum, a separable head for each end thereof, a pair of lagging sections adapted to fit about said drum, means by which said heads, drum and lagging sections may be secured together as a unit, and supplemental wedge means for holding the lagging sections against turning movement upon the drum.

8. In combination with a winding drum, a separable head for each end thereof, a pair of lagging sections adapted to fit about said drum, means by which said heads, drum and lagging sections may be secured together as a unit, and wedge shaped lugs carried upon the inner face of said ends of the drum adapted for entering notches in the abutting edges or ends of the lagging sections for further securing said lagging sections against turning movement with respect to the drum.

9. In combination with a winding drum, a separable head abutting each end of the winding drum, a pair of lagging sections adapted to fit about said drum, means by which said heads, drums and lagging sections may be secured together as a unit, one of said lagging sections having a plurality of recesses arranged adjacent each of its longitudinal edges, a screw for each recess having its head disposed therein and threaded through the edge of the lagging section in which the recess is made and then threaded into the adjacent and abutting edge of the other lagging section whereby the lagging sections are drawn together.

LEWIS CARLISLE MILES.
